[57] CLAIM

The ornamental design for a Christmas tree holder, as shown and described.

DESCRIPTION

FIG. 1 is a front elevational view of a Christmas tree holder showing my new design, all sides being identical, the partially shown pattern representing cable is understood to repeat uniformly over the entire area;
FIG. 2 is a top plan view thereof;
FIG. 3 is a bottom plan view thereof.

FIG. 1

FIG. 2

FIG. 3
